(57) **CLAIM**

The ornamental design for an exercise bike part, as shown and described.

DESCRIPTION

FIG. 1 is a front, right and top perspective view of an exercise bike part, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1; and,

FIG. 10 is a front, left and top perspective view of the exercise bike part in use.

The broken lines depict environment and portions of the exercise bike part that form no part of the claimed design. In addition, the dot-dash broken lines in FIGS. 1 and 9 depict the boundary of the detail view that form no part of the claimed design.

1 Claim, 10 Drawing Sheets
